(57) **CLAIM**

The ornamental design for a fuel dispenser container, as shown and described.

DESCRIPTION

This design patent application is related to a non-provisional application Ser. No. 11/893,206 titled Fuel Dispenser System filed concurrently with this application.

FIG. 1 is a perspective view of a fuel dispenser container showing my new design;

FIG. 2 is a back view thereof;

FIG. 3 is a front view thereof;

FIG. 4 is a side view thereof; and,

FIG. 5 is a perspective view of the fuel dispenser container shown in condition of use.

The broken lines shown in the drawing disclosure are for illustrative purposes only and form no part of the claimed design.
